poration of Illinois

Application October 10, 1946, Serial No. 702,483

9 Claims. (Cl. 112—248)

1

The present invention relates to an improved take-up mechanism for sewing machines, and more particularly to a take-up of the rotary type applied to a lockstitch machine for the control of the needle thread thereto.

The invention is herein disclosed as embodied in a preferred form in a lockstitch sewing machine of the general type consisting of a reciprocating eye needle and a rotary looper which is driven through two revolutions for each needle reciprocation. The needle thread take-up mechanism of the machine, consists of a rotary thread take-up plate having a cam-like thread engaging edge across which the thread is drawn, a rotary take-up element rotatable with the take-up plate in a circular orbit, and a relatively stationary take-up element cooperating therewith. The cam-like take-up member and the orbitally moving element operate in combination to produce an efficient take-up action which is closely adjusted to the operation of the rapidly moving rotary hook. Machines of the general type described, are adapted for operation at extremely high speeds which may approximate five to six thousand stitches and upward per minute.

It is a principal object of the present invention to provide an improved housing and supporting means for a take-up of this general description, which will fully enclose and will shield the moving parts of the take-up mechanism to the fullest extent, thereby avoiding any tendency toward concentrating or channelling the flow of air created by the rapid movement of the take-up parts which might tend to increase the operating load or to interfere with the proper handling of the thread. The arrangement is, further, particularly adapted to prevent lint or thread from being drawn into the take-up housing or being blown outwardly to annoy the operator. Moreover, the moving parts of the take-up are so shielded from view as not to distract the operator, and the operator is thoroughly protected against entanglement of hair, head, or fingers.

It is another object to provide a thread take-up mechanism of the general type indicated, having an improved housing with the foregoing advantages and which is so formed as to provide ready access to the devices within for the threading of the take-up in a simple and easy manner. Specifically, in accordance with the invention, applicant provides an improved arrangement of the needle thread take-up mechanism, including the above indicated improved construction of the housing assembly and an arrangement of certain thread guides, which will adapt those portions of

2

the needle thread handling devices, including the take-up, for rapid and easy threading without the necessity for removing or disassembling machine parts or of threading through eyelets in such parts of the mechanism where breakage is most likely to take place.

Other objects, features, and advantages of the invention will appear from a detailed description of an illustrative form of the same which 10 will now be given in conjunction with the accompanying drawings, in which:

Fig. 1 is a longitudinal, vertical section through the illustrative machine taken substantially along the line 1—1 of Fig. 3;

15 Fig. 2 is a view in left end elevation of the machine, but with the cover plate for the sewing head and the take-up mechanism removed to show underlying parts;

Fig. 3 is a view in left end elevation of the 20 machine, a portion of the work supporting base having been broken away and sectioned to illustrate the rotary hook and work feeding devices;

Fig. 4 is a fragmentary view, on an enlarged 25 scale, in front elevation of the sewing head, illustrating particularly the needle thread control and take-up devices;

Fig. 5 is a detail view, looking from the right 30 in Fig. 4, of the needle thread take-up housing with the associated thread guides removed from the machine;

Fig. 6 is a view in left end elevation of the 35 needle thread take-up mechanism with the outer cover removed and a part of the housing in section, the parts being shown in the position assumed when the needle is through the work and the rotary hook is at the beginning of its loop seizing stroke; and

Fig. 7 is a view similar to Fig. 6, but with the 40 inner cover plate for the cam-like rotary take-up member removed, and with the supporting arm for the stationary thread positioning element broken away.

The invention has been illustrated in connection with a lockstitch sewing machine of the type shown and described in the Christensen and Rubel Patent No. 2,113,572, granted April 12, 1938. This machine comprises a main frame having a base portion 10 providing a work supporting surface and a vertical standard 12 from the upper end of which extends a substantially horizontal overhanging arm 14. Power is supplied to the machine through a combined hand wheel and pulley 16 secured to the outer end of 50 a shaft 18 mounted to turn in bearings provided 55

in standard 12 and overarm 14. Shaft 18 extends substantially the full length of the overhanging arm into a needle head 24 at the free end of the arm. By means of a crank 26 mounted on the end of the shaft 18 at the needle head, power is transmitted through a pitman 28 to a needle bar 30 adapted for vertical reciprocation in suitable bearings. At its lower end the needle bar is provided with a thread-carrying needle 32.

Power is also transmitted from the shaft 18 to various operating means within the base of the machine. For this purpose a gear 34 secured to the shaft within the upper end of the standard meshes with an idler gear 36 which in turn meshes with a pinion 38 secured to a shaft 40 mounted in suitable bearings in the base. A gear 42 secured to the shaft 40 at an intermediate point, meshes with a pinion 44 secured to a hook shaft 46. At the outer end of this shaft there is mounted the rotary component of a rotary hook 48 which may be of any suitable construction. The gearing 42 and 44 is such that the hook shaft 46 will be given two revolutions for each revolution of the shaft 40. Accordingly, the rotary component of the hook will be given two revolutions for each reciprocation of the needle 32 in the formation of stitches. Also driven by the shaft 40, by connections not fully disclosed, but similar to those provided in said Christensen and Rubel patent, is a four-motion feed dog 50 mounted on a feed bar 52. The latter is pivotally connected with a feed rocker 54 adapted to be oscillated by the shaft 40 to produce the feeding and return movements of the feed dog. Other means operated by the shaft 40 are provided for lifting and lowering the feed dog in properly timed relation. For further details as to any of the foregoing construction, reference may be had to said Christensen and Rubel patent.

Cooperating with the feed dog is a presser foot 55 carried by a vertically disposed presser bar 56 which is yieldably urged downwardly by a spring 58 acting against a collar 60 secured to the presser bar. Lifting of the presser bar may be accomplished in any suitable manner to enable the introduction and removal of the work. Means for this purpose may be controlled manually or by foot treadle operation, or both. Raising of the presser bar may, for example, be accomplished by a lever 62 supported on a presser foot rock shaft 64 and having a pin and slot connection with a link 66 which at its lower end is connected by a pin 68 with a sleeve 70 slideable on the presser bar 56. Rocking movement of shaft 64 may be effected by means of a laterally extending arm 72 on shaft 64 and a treadle-actuated rod 74.

The needle thread take-up mechanism provided with the illustrated machine, consists of a thread take-up drive shaft 16 (Figs. 1 and 2) supported by a bearing sleeve 17 and connected to be driven from the shaft 18 through gears 19 and 20 mounted respectively on the two shafts. The construction is such that for each revolution of the shaft 13, there will be one revolution of the shaft 16. The outer end of the latter is formed with a flange 22 which is preferably integral with the shaft. To the flange 22 is secured a rotary take-up member 24, the latter being attached in any suitable way, as by screws 26 (see Figs. 6 and 7). The member 24 is of flat plate-like construction, and has its outer edge in the form of a smooth cam surface. The member 24 is so shaped as to constitute a two-lobed cam. To reduce the weight of the member as much as possible, it is cut out to a substantial extent, and may suitably

be provided with openings 88, 90, 92, and 94. Between openings 90 and 92 and at one side of the axis of the take-up member, there is mounted directly on this member, a thread engaging take-up element 96 which may be attached to the member 84 by means of rivet portions at the base of the element. Element 96 thus travels around a circular orbit as the cam edged take-up member 84 is rotated about the axis of shaft 76. A slot 109, defined by walls 102, 104 of arcuate form having their center of curvature at the axis of the shaft 76, is provided completely across the outer end of the element 96. This slot is quite deep, and may suitably extend about two-thirds of the distance from the outer end of the element toward the member 84. The peripheral surface of element 96 is oval in cross section, and is of reduced circumference intermediate its ends. It tapers inwardly from the outer and inner ends of the element in hour-glass fashion, and thus provides a cavity or depression having its root or bottom 106 (Fig. 1) in a central plane into which the thread will naturally fall as it is picked up by the element.

The thread is supported at times, during movement of the rotary take-up element 96, in the orbital path of the latter by means of a stationary thread positioning element 107 which, as best shown in Fig. 6, consists of an angled plate having a supporting portion parallel with the member 84 and an inwardly projecting, bent-over portion arcuately shaped and positioned to pass through the slot 109 in the rotary take-up element 96. The upper end of the inwardly projecting portion is formed with a relatively deep thread positioning notch 103. Lower edge 108a of the inwardly projecting portion of element 107 serves as a thread throw-off by camming the thread outwardly over the end of element 96 in the event of breakage of the thread and winding of it on the take-up element 96. A knife element 109 is effective at this time to sever the thread. Inasmuch as a take-up mechanism embodying a cam-like take-up member, an orbital take-up element, a stationary positioning element and a thread throw-off and severing knife, substantially as above described, has been fully described and claimed in the application of Charles F. Rubel, Serial No. 581,980, filed on March 10, 1945, now Patent No. 2,446,245, granted August 3, 1948, further detailed description of the operation of this mechanism is believed unnecessary.

In the improved form of needle thread take-up mechanism shown, the take-up member 84 is wholly enclosed by a hood, the rear wall of which is formed by a plate 110 secured to the end face of the needle head by screws 112 (Fig. 3). The outer peripheral wall of the hood takes the form of an arcuate band 114 which extends substantially around the take-up member 84 in a full circle, except for a short section through which passes a bracket 116 hereinafter more fully to be described. The band 114 is formed integrally with the plate 110 and is preferably curved in an axial direction also, as best shown in Fig. 4. The rotary take-up member 84 is partially enclosed at its outer side by means of a plate or inner cover 118 of circular outer contour, to fit within the band 114, and having the middle portion thereof cut out to provide a large central opening which extends outwardly to the periphery of the plate over approximately one-quarter of the circumference of the housing. Plate 118 is secured to the housing or hood by means of machine screws 120 which pass through the plate

and are screw-threaded into ears 122 carried by the peripheral enclosing band 114. The plate 118 encloses the outer peripheral portions of the take-up member 84, and has the center portion thereof cut away sufficiently to avoid interference with the orbital take-up element 96. An outer cover 124 shields and substantially encloses the central portion of the outer face of the hood. It is, however, separated from the cover 118 for convenience of threading and for permitting free discharge of the air currents produced by the orbitally movable take-up element 96.

The bracket 116 referred to, is bolted by means of screws 126 to the plate 110, is constructed and arranged to enclose the lower portion of the compartment within which the rotary take-up member 84 is mounted, and provides support for a number of associated parts of the take-up assembly including the outer cover 124 which is secured to the bracket by screws 128. The bracket 116 provides support also for the thread positioning element 107 and the thread severing knife 109. The thread positioning element 107 is formed with a downwardly extending shank portion secured by screws 134 to an upward extension of the bracket 116. This shank portion is provided with an elongated slot 135 of slightly greater width than the diameter of the screws 134 so that the element 107 is capable of adjustment to a limited extent both longitudinally and transversely of the slot 135 and angularly about either of the screws 134, to insure proper cooperation with the element 96. The thread severing or knife element 109 is provided with an offset shank portion, which is fastened by a screw 138 to the forward edge of bracket 116, and with a projecting end which extends through an aperture 140 formed in the positioning member 107. In the illustrated form of the invention, the bracket 116 is further provided at its upper end with an extension in which is formed a transverse slot providing a self-threading thread guide 142 which serves to guide the thread passing from the cam-like edge of the take-up member 84 to the notch 108 in the positioning element 107 and to the rotary take-up element 96. A guard or cover plate 144 fastened by screws 146 to the forward edge of the bracket 116 encloses a portion of the casing not enclosed by the plate 118 and may be regarded as a continuation of this inner cover.

The needle thread is drawn from a spool or other source of supply to an apertured guide 150 secured to the plate 110 of the take-up housing (Figs. 4 and 5). After traversing several holes in this guide, the thread is passed around a thread tensioning device 152, which may be of conventional construction, over a check wire 154 forming part of the thread tensioning device, and then around a thread guide 156 provided by a crooked downwardly extending arm. The thread guide 156 and the thread guide 142 above referred to, provide support for the thread at opposite sides of the take-up member 84, and cooperate with the camming edge of said member to exert a take-up action upon the thread. From an inspection particularly of Figs. 3, 4, and 5, it will be noted that the stationary thread guides 156, 142 are disposed adjacent to and are readily accessible, respectively, from the outside of the rear wall or plate 110 of the housing, and from outside of the guard plate 118 forming the forward wall of the housing for the rotary take-up member 84. A slot or aperture designated at 158 (Figs. 4 and 5) is formed in the housing and extends inwardly through the peripheral band 114 and

plate 110 with its throat approximately in line with the stationary thread guides 156, 142. A similar aperture is formed in the guard surface enclosing the outer face of the take-up member 84 between the cover plate 118 and the auxiliary cover plate 144. This aperture or slot is approximately in line with the guides 156, 142 and connects with the path of movement of the take-up element 96 (see particularly Fig. 6), so that free passage is permitted to the thread from the stationary thread guide 156 across the camming edge of the take-up member 84 to the thread guide 142. From the thread guide 142, the thread passes through or above the notch 108 in the thread positioning member 107, then around the rotary take-up element 96, and downwardly through a guide slot 160, formed in the band 114 outwardly of the cover plate 118, to the eye of the needle.

With the improved form of take-up device herein provided, the outer cover 124 is constructed and arranged to cooperate with the associated rotary take-up element 96 in an improved and more efficient manner, to provide for an adequate control of the thread engaged by the take-up element and, at the same time, to avoid objectionable air currents in the casing. The improved form of outer cover has a surface 162 cooperating with and closely adjacent to the path of the outer end of the orbital take-up element 96. This portion of the cover which is of reduced thickness, continues outwardly to the edge of the cover. A relatively raised or thick inside portion of the outer cover, which is bounded by the surface 162, provides an annular thread guiding shoulder to position or retain the thread properly with relation to the rotary take-up element 96 and stationary thread positioning member 107. The improved construction, including the surface 162 extending to the outer periphery of cover 124, has the substantial advantage that it eliminates, or reduces to a minimum, the tendency of the take-up element 96 to act as a fan when moving at extremely high speeds. With the improved construction any air currents which may be generated by the rotation of the take-up element 96 are effectively dissipated away from the operator and away from the regions in which it might interfere with the handling of the thread.

The improved construction of the needle thread take-up, as above described, moreover, has the advantage of providing a complete enclosure for all moving parts of the take-up, including the entire thread engaging edge of the rotary take-up member 84. At the same time, provision is made for rapid and easy threading of the take-up which eliminates any necessity for removing any parts or of passing the thread through closed thread eyes in this portion of the machine, where thread breakage is most likely to occur. With the illustrated construction, the threading of the take-up is readily and quickly accomplished by passing a suitable length of the thread transversely under the end of the fixed thread guide 156, through the open slot 158 and over the edge of the take-up member 84, into the slotted thread guide 140, then around the passage between the peripheral edge of the cover member 124 and the outer surface of plate 118, thence through the slot 160, and finally downwardly to the needle which is threaded in the usual manner.

While an illustrative form of the invention has been described in considerable detail, it will be understood that numerous changes in the construction and arrangement of the several parts,

and in the general application of the invention, may be made, without departing from its principles and scope. The terms and expressions used herein have been employed as terms of description and not of limitation.

What is claimed is:

1. In a sewing machine, needle thread take-up means comprising a rotary take-up member having a cam-like thread engaging edge, a take-up element movable with said take-up member in an orbital path, a housing for said take-up means including a rear wall, a peripheral wall substantially enclosing the edge of said take-up member, an inner cover enclosing outwardly disposed front face portions of said take-up member and substantially surrounding the axis thereof, and an outer cover overlying said orbitally movable take-up element, and spaced from the inner cover, said peripheral wall and rear wall and inner cover being formed to provide an inwardly extending transverse thread receiving slot, and thread guiding means including a pair of stationary self-threading thread guides arranged at opposite sides of said take-up member along a line passing through said transverse slot for guiding the thread across the edge of the take-up member and thence to said take-up element.

2. In a sewing machine, needle thread take-up means comprising a rotary take-up member having a cam-like thread engaging edge, a take-up element movable with said take-up member in an orbital path, a housing for said take-up member enclosing substantially the entire peripheral edge, the rear face and outer portion of the outer face of said member, an outer cover overlying said orbitally movable take-up element and spaced from said housing, said housing being formed with a transverse thread receiving slot extending inwardly of said housing from its outer edge, and thread guiding means including a pair of stationary thread guides arranged at opposite sides of said take-up member along a line passing through said transverse slot for guiding the thread across the edge of the take-up member and thence to said take-up element.

3. In a sewing machine, needle thread take-up means comprising a rotary take-up member having a cam-like thread engaging edge, a take-up element mounted on the face of said take-up member for movement therewith in an orbital path, a housing for said take-up member enclosing substantially the entire peripheral edge, the rear face and portions of the outer face of said member outwardly of the orbital path of said take-up element, an outer cover overlying said orbitally movable take-up element and spaced from said housing, said housing being formed with a transverse thread receiving slot extending inwardly of said housing from the outside edge thereof and providing an unobstructed thread passage into the path of said rotary take-up member, and thread guiding means including a pair of stationary self-threading thread guides arranged at opposite sides of said take-up member along a line passing through said transverse slot for guiding the thread across the edge of the take-up member and thence to said take-up element.

4. In a sewing machine, needle thread take-up means comprising a rotary take-up member having a cam-like thread engaging edge, a take-up element mounted on the outer face of said take-up member for movement therewith in an orbital path, a stationary thread supporting element in said orbital path, a housing for said take-up mem-

ber enclosing substantially the entire peripheral edge, the rear face and portions of the outer face of said member outwardly of the orbital path of said take-up element, an outer cover overlying said orbitally movable take-up element and spaced from said housing, a bracket supporting said stationary thread positioning element, and outer cover, said housing being formed with a transverse thread receiving slot extending inwardly of said housing from the outside edge thereof and providing an unobstructed passage into the path of said rotary take-up member, and thread guiding means including a thread guide at the rear face of the take-up member and a thread guide at the outer face of the take-up member on said bracket in line with said transverse slot for guiding the thread across the edge of the take-up member and thence to said stationary thread supporting element and orbitally movable take-up element.

5. In a sewing machine, needle thread take-up means comprising a rotary take-up member having a cam-like thread engaging edge, a take-up element mounted on the outer face of said take-up member for movement therewith in an orbital path, a stationary thread supporting element associated with said take-up element, a housing for said take-up member enclosing substantially the entire peripheral edge of said member and the outer face of said member outwardly of the orbital path of the take-up element, an outer cover overlying said orbitally movable take-up element and spaced from the housing, said housing being formed with a transverse thread receiving slot extending inwardly of the housing from the outside edge thereof and providing an unobstructed passage into the path of said rotary take-up member, and thread guiding means including thread guides at opposite sides of the take-up member in line with said transverse slot for guiding the thread across the edge of the take-up member and thence to said stationary thread supporting element and orbitally movable take-up element.

6. In a sewing machine, needle thread take-up means comprising a rotary take-up member having a cam-like thread engaging edge, a take-up element mounted on the face of said take-up member for movement therewith in an orbital path, a stationary thread supporting element associated with said take-up element, a housing for said take-up member enclosing substantially the entire peripheral edge, the inner face and the outer face of said member outwardly of the orbital path of the take-up element, an outer cover overlying said orbitally movable take-up element and spaced from said housing, said housing being formed with a transverse thread receiving slot extending inwardly of the housing from the outside edge thereof and providing an unobstructed passage for the thread into the path of said take-up member, thread guiding means including self-threading thread guides at opposite sides of the take-up member in line with said transverse slot for guiding the thread across the edge of the take-up member and thence to said stationary thread supporting element and orbitally movable take-up element, and a fixed bracket providing support for the outer cover, the stationary thread supporting element and said thread guide at that side of the take-up member adjacent said outer cover.

7. In a sewing machine, needle thread take-up means comprising a rotary take-up member having a cam-like thread engaging edge, a take-up

element supported for movement with said take-up member in an orbital path, a housing for said take-up member enclosing portions of the outer face of said member outwardly of the orbital path of said take-up element, guiding means including thread guides arranged to guide the thread across the edge of the taken-up member and thence to said take-up element, and an outer cover overlying said orbitally movable take-up element and spaced from said housing, said cover having an outer flat rim portion and a thicker central portion providing an annular shoulder extending inwardly within the path of movement of said take-up element, said central portion providing a thread confining surface for retaining the thread on said take-up element.

8. In a sewing machine, needle thread take-up means comprising a rotary take-up member having a cam-like thread engaging edge, a take-up element supported on the outer face of said take-up member for movement therewith in an orbital path, a housing for said take-up member enclosing substantially the entire peripheral edge of said member and portions of the outer face thereof outwardly of the orbital path of said take-up element, said housing having formed therein a transverse thread receiving slot extending inwardly from the edge of the housing and providing an unobstructed passage to said take-up member, guiding means including thread guides arranged at opposite sides of said take-up member to guide the thread into said slot across the edge of the take-up member and thence into the path of said take-up element, and an outer cover overlying said orbitally movable take-up element spaced from said housing, said cover having a flat surface

5

disposed adjacent and parallel with the orbital path of the outer end of said take-up element and having an annular shoulder extending inwardly within said orbital path, said outer cover being arranged to cooperate with the radial inward side and the outer end of said take-up element to retain the thread thereon.

9. In a sewing machine, needle thread take-up means comprising a rotary take-up member having a cam-like thread engaging edge, a take-up element supported on the outer face of said take-up member for movement therewith in an orbital path, a housing for said take-up member having a rim substantially completely surrounding the same, a support member extending through said rim and carrying radially inwardly thereof a thread guide arranged to direct the thread into the path of said element, a thread retaining and removing element carried by said support in the path of said take-up element, and a thread severing element carried by said support in position to sever thread removed from said take-up element.

Certificate of Correction

Patent No. 2,511,081

June 13, 1950

CHARLES F. RUBEL

It is hereby certified that errors appear in the printed specification of the above numbered patent requiring correction as follows:

Column 1, line 33, for the word "movement" read *movements*; column 9, line 7, for "taken-up" read *take-up*;

and that the said Letters Patent should be read with these corrections therein that the same may conform to the record of the case in the Patent Office.

Signed and sealed this 26th day of September, A. D. 1950.

[SEAL]

THOMAS F. MURPHY,
Assistant Commissioner of Patents.
